UNITED STATES PATENT OFFICE.

PAUL FRAZER, OF WILMINGTON, DELAWARE.

DRIP-CUP.

1,264,049.

Specification of Letters Patent. Patented Apr. 23, 1918.

Application filed November 20, 1915. Serial No. 62,626.

To all whom it may concern:

Be it known that PAUL FRAZER, a citizen of the United States, residing at Wilmington, in the county of New Castle and State 5 of Delaware, have invented new and useful Improvements in Drip-Cups, of which the following is a specification.

This invention relates to improvements in umbrellas and has relation more particularly 10 to a drip cup for umbrellas.

The primary object of the invention is the provision of a device of this character which may be readily and quickly attached or detached to the umbrella tip in such a manner, 15 whereby when the umbrella is in a closed position, the water draining therefrom will be deposited in the drip cup and prevented from dripping on the floors of buildings, such as theaters, apartments, stores and the 20 like.

A still further object of the invention is the provision of a device of this character, wherein a protector is detachably connected with the cup to prevent the breakage of the 25 same should the umbrella be accidentally dropped and engage with the pavement when the umbrella is in a collapsed position.

The invention consists in the novel features, details of construction and combination of parts which will hereinafter be more fully set forth, illustrated in the accompanying drawing and pointed out in the appended claims.

In the accompanying drawing:

35 Figure 1 is a view illustrating the drip cup attached to the tip portion of an umbrella, the drip cup being shown in section;

Fig. 2 is a section taken on line 2—2 of Fig. 1;

40 Fig. 3 is a section taken on line 3—3 of Fig. 1;

Fig. 4 is a plan view of the drip cup with the protector removed therefrom; and

45 Fig. 5 is a detail perspective of the fastening member for fastening the protector to the drip cup.

Referring more particularly to the drawing, A denotes the umbrella, and B the tip thereof.

50 In the accompanying drawing, 5 designates my improved drip cup which may be made of any suitable material such as hard rubber or the like, and comprises a hollow cylindrical body portion or receptacle 6 forming within the cup a catch basin 7 for the collection of the drippings or drainings

of the umbrella when the latter is in a closed or set up position. The body portion 6 is formed with a closed upper end 8 and a lower open end 9 having an interiorly 60 threaded portion 10. The open end 9 of the cup is closed by means of a cap 11 having threaded engagement with the threaded portion 10 of the casing, for permitting of the connection or removal of the cap with said 65 casing. This cap is provided with an enlarged central opening 12 which is of a diameter greater than the diameter of the tip of the umbrella, whereby defining between the tip and the walls of the opening, drainage receiving spaces 13, which permits of the water from the umbrella, when the latter is in a collapsed position, to drain therefrom and through the opening 12 and be deposited within the cap basin 7 of the body portion 6. 70 75

Positioned within the body portion 6 and in close proximity with the closed end 8 thereof, is a cup 14 which is of substantially rectangular configuration and formed with a bowl 15. The walls of the cup 15 are 80 formed with a plurality of opposite diametrically disposed threaded openings 16 adapted to receive the locking screws 17. Said screws are threadedly mounted in the cup 14 and upon the adjustment of the 85 same in an inward lateral direction will cause the same to impinge against the tip B of the umbrella for locking the drip cup thereto. The cup 14 is formed with an annular base flange 18, of a diameter slightly 90 less than the diameter of the body portion 6 of the drip cup and frictionally engages with a rubber disk 19, the latter being seated upon the inner surface of the closed end 8 of the body portion 6, and is primarily 95 adapted to absorb any jars, shocks or the like which the drip cup might be subject to, and preventing the loosening of the locking screws 16. Depending from the central portion of the bottom of the cup 14 100 is an internally threaded socket 20 which protrudes through the central aperture 21 of the disk 19, and thence through the central opening 22 of the closed end 8 and terminates flush with the exterior surface of 105 the closed end 8.

I provide for the cup a protector 23 made preferably of soft rubber and is primarily adapted for preventing the breakage of the cup upon any accidental dropping of the 110 umbrella or the contacting of the cup with the pavement or the like when the umbrella

is in a closed or collapsed position. Embedded on the protector 23 is a fastening plate 24 formed with a centrally located upwardly threaded shank 25, the latter being adapted to threadedly engage in the internally threaded socket 20 for detachably connecting the protector with the cup 14. The fastening plate 24 is provided with a pair of substantially rectangular lugs 26, disposed to opposite sides of the threaded shank 25 and alining transversely therewith, and adapted to engage in depressions 27 formed in the exterior face 28 of the closed end 8 of the body portion 6, when the protector is tightly screwed on the cup thereby preventing any accidental retrograde movement of the protector.

From the foregoing description taken in connection with the accompanying drawing, the advantages of construction, and the methods of operation will be readily apparent to those skilled in the art to which the invention relates, and while I have described the principles of operation of the invention together with the device which I now consider to be the best embodiment thereof, I desire to have it understood that the device shown is merely illustrative, and that such changes may be made when desired as are within the scope of the claims appended thereto.

What is claimed as new is:—

1. A drip cup for umbrellas comprising a

cylindrical body portion having a closed end formed with a centrally located opening, a cup mounted in said body portion, cushioning means between the closed end of the body and said cup, locking means carried by said cup for securing the latter to the tip portion of the umbrella, a threaded socket depending from said cup and protruding through the cushioning means and the opening in the closed end of said body, a protector, and a fastening plate embedded in said protector having a portion thereof threadedly engaging in the socket of the cup for connecting the cup to said drip cup.

2. A drip cup for umbrellas comprising a body portion having a closed end formed in the exterior surface thereof with a pair of diametrically arranged recesses, means mounted in said cup for locking the drip cup to said umbrella, a protector, and a fastening plate embedded in the protector and formed with a pair of diametrically disposed lugs adapted, upon the threaded engagement of the fastener with the drip cup, to co-act or engage with the recesses in the closed end wall of the cup and for preventing any rotary movement of said protector.

In testimony whereof I affix my signature in presence of two witnesses.

PAUL FRAZER.
